UNITED STATES PATENT OFFICE.

RICHARD MURRAY, OF NEW YORK, N. Y.

FLOOR AND CEILING CONSTRUCTION.

Application filed May 20, 1926. Serial No. 110,396.

This invention relates to floor and ceiling constructions for buildings of any kind or class, and the object of the invention consists in the provision of a plurality of sheet metal strips or sheets of such width as to form ceiling panels or strips and also fashioned to form the joist of a floor, said strips or sheets including the joist portions, preferably extending from one beam to another, or from one wall to another, that is to say, from an outer wall to a partition wall or other intimate wall; a still further object being to provide means whereby a floor facing of any kind or class may be mounted in connection with and supporting upon the joist, and still further whereby the space between the joist and above the ceiling strips may be filled in with a suitable material, for example concrete; and a still further object being to provide means whereby the lower face of the ceiling strips or sheets may be fashioned to permit of the application of a ceiling facing or covering; and with these and other objects in view the invention consists of a device of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a diagrammatic, sectional view illustrating a part of two walls with my ceiling and floor forming construction mounted in connection therewith;

Fig. 2 is a partial section on the line 2—2 of Fig. 1 and on an enlarged scale, showing the ceiling partially in perspective;

Fig. 3 is a view similar to Fig. 2 but showing a modification;

Fig. 4 is a perspective detail view of the strips or sheets shown in Figs. 1 and 2;

Fig. 5 is a perspective view of one of the strips or sheets shown in Fig. 3; and,

Fig. 6 is a sectional detail view of a part of a sheet showing another modification.

In Fig. 1 of the drawing, I have indicated at 10 and 11 two walls of a building, both of which are inner walls, in the construction shown, and in the wall 10 is a steel beam or girder 12 and a similar beam or girder 13 is in the wall 11. In the construction of the

building and in forming the floor and ceiling structure in accordance with my invention, as shown in Figs. 1, 2 and 4 of the drawing, I mount upon the top of the beams 12 and 13, metal strips or sheets 14 which extend from one beam 12 to the other beam 13 in the manner indicated in Fig. 1 of the drawing, the ends of said strips or sheets being imbedded in the wall structure as will be apparent, and as seen in said figures, the strips or sheets 14 consist of comparatively wide ceiling forming portions 14^a, at one end of which the sheet is bent backwardly upon itself as seen at 14^b, and then upwardly at right angles to the sheet 14^a as seen at 14^c to form a joist member having a flanged top 14^d. The side portion 14^e of the sheet is straight, as seen in Figs. 2 and 4 of the drawing, and in assembling the separate sheets in the construction of a floor and ceiling, the side portion 14^e is placed upon the inwardly turned flange portion 14^b, as clearly seen in Fig. 2 of the drawing, and when the separate strips have all been placed in position, it will be apparent that a floor and ceiling frame structure, comprising ceiling facing portions 14^a and spaced joist portions or members 14^d, will result.

The flanged side portions 14^b of the sheets 14 may form a panel or beam-like effect for the ceiling structure, or suitable facings or coverings may be applied to give a smooth and finished effect in the manner illustrated in Fig. 3 of the drawing, and later described.

A flooring 15 of any kind or class is mounted upon the flanged upper ends 14^d of the joist portions 14^c, and as illustrated in Fig. 2 of the drawing this flooring may be of concrete, tiling, boards, slabs or the like, and as shown is also mounted upon a body 16 contained within and between the joist members 14^c and above the ceiling forming portions 14^a. This body 16 may be composed of concrete or any other suitable material, it being understood that the strips or sheets employed will be of such strength as to sustain the body 16, and further to provide the necessary floor strength, which results may be accomplished by gaging the thickness of the sheet metal employed, and further by the distance arranged between the joist members, 14^c, and still further by reinforcing said joist members, as seen in Fig. 6 of the drawing, by attaching angle plates 17 to one side face of the joist 14^c, the angle plates 17 having top flanged portions 17^a directed

in opposite directions to the flanged tops 14^a of the joist 14^c. It will be understood that a floor and ceiling construction may be made up of a combination of the joist structures, as seen in Figs. 2 and 6, that is to say, the reinforced joists may be incorporated at intervals with the single joist, for example every other joist may be reinforced, or every third joist reinforced as the case may require.

10 In Figs. 3 and 5 of the drawing, I have shown a modification in the formation of the strips or sheets 14, wherein I have substituted for the straight edge portion 14^b an offset edge portion 14^f, the offset being upward to compensate for the two thicknesses of metal at the flanged side portion 14^b, whereby when the separate strips or sheets are placed together, a straight and flush ceiling surface is provided, as clearly seen in 15 Fig. 3 of the drawing. In this form of construction I have also illustrated apertures 18 in the ceiling forming portions 14^a of the strips or sheets, whereby a ceiling surface or body 19 of any suitable material may be applied to the strips or sheets and anchored thereto, by the passage of the body or substance 19 through the apertures 18 provided, as indicated at 20 in Fig. 3 of the drawing.

20 In Fig. 3 of the drawing I have also shown another manner of securing, preferably a board flooring to the joist 14^c, which consists in mounting wooden strips or slabs 21 upon the top flanges 14^d of the joist and nailing or otherwise securing a board flooring 22 there- 25 to. However, I am not necessarily limited to any specific manner of constructing the floor surface or attaching and supporting the same to the joist, and various changes in and modifications of the construction herein 30 shown and described may be made, within the scope of the appended claims, without departing from the spirit of my invention or sacrificing its advantages.

Having fully described my invention, what 35 I claim as new and desire to secure by Letters Patent, is:—

1. A ceiling construction for buildings fashioned from a plurality of interlocking members adapted to extend from one wall 40 to another, said members being formed from strips of sheet metal, one side of said strips being folded upon itself to form a projecting flange of two thicknesses of the metal of said strip, and a part extending substantially 45 at right angles to one face of said strip, and a flange at the free edge of said part, said part forming a joist member upon which the floor surface is adapted to be supported.

2. A ceiling construction for buildings 50 fashioned from a plurality of interlocking members adapted to extend from one wall to another, said members being formed from strips of sheet metal, one side of said strips being folded upon itself to form a projecting flange of two thicknesses of the metal

55 of said strip, and a part extending substantially at right angles to one face of said strip and a flange at the free edge of said part, said part forming a joist member upon which the floor surface is adapted to be supported, and said last named flange extending in a direction opposite that of the first named flange.

3. A ceiling construction for buildings 60 fashioned from a plurality of interlocking members adapted to extend from one wall to another, said members being formed from strips of sheet metal, one side of said strips being folded upon itself to form a projecting flange of two thicknesses of the metal of said strip, and a part extending substantially at right angles to one face of said strip and a flange at the free edge of said part, said part forming a joist member upon which the floor surface is adapted to be supported, and said last named flange extending in a direction opposite that of the first named flange, and the other side edge of said strips being adapted to engage the first named flange or an adjacent strip in the construction of the ceiling.

4. A ceiling construction for buildings 65 fashioned from a plurality of interlocking members adapted to extend from one wall to another, said members being formed from strips of sheet metal, one side of said strips being folded upon itself to form a projecting flange of two thicknesses of the metal of said strip, and a part extending substantially 70 at right angles to one face of said strip and a flange at the free edge of said part, said part forming a joist member upon which the floor surface is adapted to be supported, and said last named flange extending in a direction opposite that of the first named flange, and the other side edge of said strips being adapted to engage the first named flange or an adjacent strip in the construction of the ceiling, and means for reinforcing the joist member 75 of said strips.

5. A ceiling construction for buildings 80 fashioned from a plurality of interlocking members adapted to extend from one wall to another, said members being formed from strips of sheet metal, one side of said strips being folded upon itself to form a projecting flange of two thicknesses of the metal of said strip, and a part extending substantially 85 at right angles to one face of said strip and a flange at the free edge of said part, said part forming a joist member upon which the floor surface is adapted to be supported, and said last named flange extending in a direction opposite that of the first named flange, and the other side edge of said strips being 90 adapted to engage the first named flange or an adjacent strip in the construction of the ceiling, and means whereby the lower faces 95 of said strips when coupled together to form the ceiling, may be flush and parallel.

6. A ceiling construction for buildings fashioned from a plurality of interlocking members adapted to extend from one wall to another, said members being formed from 5 strips of sheet metal, one side of said strips being folded upon itself to form a projecting flange of two thicknesses of the metal of said strip, and a part extending substantially at right angles to one face of said strip and a 10 flange at the free edge of said part, said part forming a joist member upon which the floor surface is adapted to be supported, said last named flange extending in a direction opposite that of the first named flange, and the 15 other side edge of said strips being adapted to engage the first named flange or an adjacent strip in the construction of the ceiling, and said strips being apertured, and plaster or other finishing surfaces applied to the lower face thereof in forming 20 the complete ceiling.

7. A ceiling construction for buildings

fashioned from a plurality of interlocking members adapted to extend from one wall to another, said members being formed from 25 strips of sheet metal, one side of said strips being folded upon itself to form a projecting flange of two thicknesses of the metal of said strip, and a part extending substantially at right angles to one face of said strip and a 30 flange at the free edge of said part, said part forming a joist member upon which the floor surface is adapted to be supported, said last named flange extending in a direction opposite that of the first named flange, and the 35 other side edge of said strips being adapted to engage the first named flange or an adjacent strip in the construction of the ceiling, and a body of filling material between the joists of said strips. 40

In testimony that I claim the foregoing as my invention I have signed my name this 12th day of May, 1926.

RICHARD MURRAY.
